The ornamental design for an entryway cladding, as shown and described.

DESCRIPTION

FIG. 1 is a rear perspective view of an entryway cladding showing our new design;

FIG. 2 is a right side elevational view thereof;

FIG. 3 is a left side elevational view thereof;

FIG. 4 is a top plan view thereof;

FIG. 5 is a bottom plan view thereof;

FIG. 6 is a front side elevational view thereof; and,

FIG. 7 is a rear side elevational view thereof.

The broken lines in the drawings illustrate environmental structure that forms no part of the claimed design.
